CLAMP

Charles S. Card, Cortland, N. Y., assignor to The
Brewer-Titchener Corporation, Cortland, N. Y.,
a corporation of New York

Application April 5, 1946, Serial No. 659,835

4 Claims. (Cl. 24—135)

1

This invention relates to a functionally and structurally improved clamp and particularly a strain clamp of the snubbing type for use with cables, conductors or the like.

It is an object of the present invention to provide a clamp of this character having a body portion made in one piece which may be stamped from sheet or strip metal.

A further object is the provision of a snubbing type strain clamp which eliminates the necessity of a separate keeper or other piece for gripping the cable and in which the cable is gripped between two integral parts of the body of the clamp.

Other objects are the provision of an improved clamp which is relatively inexpensive to manufacture, which is efficient in operation and will retain the cable against accidental slippage or displacement, and which is rugged and strong and will give satisfactory service over a relatively long period of time.

Other objects will be apparent from the following detailed description of the drawing in which:

Fig. 1 is a perspective view of a clamp embodying my invention.

Fig. 2 is a sectional view in the direction of the arrows on the line 2—2 of Fig. 1.

Fig. 3 is a sectional view in the direction of the arrows on the line 3—3 of Fig. 1.

Fig. 4 is a perspective view of a blank from which the body of the clamp is made.

Figs. 5 and 6 show successive steps in the manufacture of the clamp from the blank, and

Fig. 7 is a sectional view in the direction of the arrows on the line 7—7 of Fig. 6.

My improved clamp comprises an elongated, generally loop shaped body portion indicated at 10 which is made of one piece and which may be stamped from sheet or strip metal as will be later explained.

The body portion is provided with a curved channel-shaped snubbing seat 11 which extends substantially completely around the body portion and is provided with a taut cable end and a slack cable end. The initial portion or taut cable end of the snubbing seat shown at the right-hand portion as viewed in Fig. 1 has a somewhat larger radius and the radius becomes progressively smaller through the intermediate portion. The final portion thereof is substantially straight as shown. The taut cable end of the snubbing seat bows inwardly when the clamp is supported in its normal manner so that the cable does not engage the mouth of the snub-

2

bing seat as shown in Fig. 1. This protects the cable from frictional engagement with the mouth and prevents sharp bending over the edge thereof. The snubbing seat is adapted to accommodate a cable or conductor 12 and exert snubbing action thereon. Therefore, the cross-sectional size of the seat should be such as to accommodate the cable.

The body of the clamp is also provided with an attaching portion consisting of a pair of laterally offset substantially parallel protruding wings 13 having central apertures which accommodate a pin 14 for attaching the clamp to an insulator or other suitable support.

15 Adjacent the clamp mouth or the taut cable end of the snubbing seat the body portion is provided with a laterally projecting gripping or main clamping plate 15 which cooperates with the overlapping gripping or secondary clamping 20 plate 16 formed integrally with the body portion beyond the slack cable end of the snubbing seat. The plate 15 is preferably provided with an aperture 17 near the forward end thereof to accommodate the hook of the come-along which 25 is generally used in applying the cable or conductor to the clamp.

The plate 15 is preferably disposed at an angle extending away from the plane of the snubbing seat so that the slack cable leaving the end of 30 the clamp will not interfere with the taut end of the cable entering the clamp. Gripping plate 16 is disposed at the same angle as plate 15 and the slack end of the cable is gripped between the two plates. For this purpose the two plates

35 are preferably provided with grooves 18 and 19 which accommodate and guide the cable and help to retain it in position. Clamping or gripping action is exerted on the plates by suitable fastening means such as the nut and bolt assemblies 40 indicated at 20 passing through apertures 21 and 22 in the plates.

As previously stated the clamp is made of one piece preferably by stamping from sheet or strip metal. In Figs. 4-7 I have illustrated the preferred method of making the clamp. Thus, in Fig. 4 I have illustrated a blank 25 which is stamped from sheet metal (preferably steel) so as to provide an elongated central portion of sufficient length and width to furnish the snubbing seat after it has been radiused and formed in the manner indicated in Figs. 5 and 6. Projecting from the end of the blank is the gripping plate 16 and from opposite sides thereof the two supporting ears 13. On the opposite end of the 55 blank from the gripping plate 16 and projecting

laterally from one side thereof is the supporting blade 15. The blank is also pierced to provide the apertures 21 and 22 for accommodating the nuts and bolts 20, the aperture 17 for accommodating the "come-along," and the apertures 23 which receive the attaching pin 14.

Thereafter the blank is radius and formed in the manner shown in Fig. 5 to provide the snubbing seat 11. The grooves 18 and 19 are impressed therein, the ears 13 are offset outwardly and plate 15 and the slack end of the seat are bent at an angle.

The final step in the manufacture of the body portion is illustrated in Fig. 6 in which the slack cable end of the snubbing seat and the plate 16 are bent around to the indicated final position with plate 16 resting on top of plate 15 and the apertures 21 and 22 in substantial alignment with each other.

The clamp is completed by providing it with the pin 14 and the nuts and bolts 20. The parts may be protected against rust by a suitable finish such as plating, galvanizing or the like. In using the clamp it is attached to an insulator or other suitable support by means of the pin 14. The taut side of the cable 12 is then wound around the snubbing seat and between the plates 15 and 16 in the grooves 18 and 19. As the cable is tightened the nuts and bolts 20 may be in position but should be loose, so as to permit the cable to freely slide between the plates. The cable is pulled taut in the usual manner by means of a "come-along," or block-and-tackle which may be attached to the clamp by a hook engaged in the aperture 17. As the cable is pulled taut the slack is taken up at the free end thereof which projects beyond the gripping plates. When the desired degree of tautness has been obtained the nuts and bolts 20 are tightened with the result that the cable is firmly clamped in position.

It should be noted that the clamp exerts both a snubbing and gripping action on the cable. Thus, the cable is positioned in the snubbing seat which extends substantially around the body of the clamp and the slack end thereof is firmly gripped between the plates 15 and 16 in the grooves 18 and 19. This double action without the aid of any separate keeper or other gripping means serves to hold the clamp against accidental slippage or displacement.

It will thus be seen that I have provided an improved clamp and method for making the same in which the clamp body is made in one piece and may be stamped from sheet or strip metal. Modifications may be made in the illustrated embodiment of my invention without departing from the invention as set forth in the accompanying claims.

I claim:

1. A clamp comprising a sheet-metal body bent upon itself to provide a main plate, a channeled cable-receiving element and a secondary plate, said plates being integral with said element and disposed at opposite ends thereof with the secondary plate beyond the channel of said element, said element having its channel extending outwardly and being curved to have said plates dis-

posed in overlapping relationship, said plates being movable with respect to each other incident to a flexing of said element and means for preventing substantial movements of said plates with respect to each other.

2. A clamp comprising a sheet-metal body bent upon itself to provide a main plate, a channeled cable-receiving element and a secondary plate, said plates being integral with said element and disposed at opposite ends thereof with the secondary plate beyond the channel of said element, said element being disposed to have its channel extend outwardly and being curved so that said plates are overlapped and extend in substantially parallel planes, said plates being movable with respect to each other incident to a flexing of said element and means extending through said plates to draw them towards each other to clamp between their surfaces an interposed cable.

3. A clamp comprising a sheet-metal body bent upon itself to provide a main plate, a channeled cable-receiving element and a secondary plate, said plates being integral with said element and disposed at opposite ends thereof with the secondary plate beyond the channel of said element, said element being disposed to have its channel extend outwardly and being curved so that said plates are overlapped and extend in substantially parallel planes, said plates being movable with respect to each other incident to a flexing of said element, at least one of said plates having its face adjacent the second plate formed with a cable-receiving groove and securing means extending between said plates and to each side of said groove for clamping between said plates an interposed cable.

4. A clamp comprising a sheet-metal body bent upon itself to provide a main plate, a channeled cable-receiving element and a secondary plate, said plates being integral with said element and disposed at opposite ends thereof with the secondary plate beyond the channel of said element, said element having its channel extending outwardly and being curved to have said plates disposed in overlapping relationship, said plates being movable with respect to each other incident to a flexing of said element, means for preventing substantial movements of said plates with respect to each other and at least one of said plates being formed with pin-accommodating and tool-accommodating apertures.
